UNITED STATES PATENT OFFICE

JAMES E. TATE, OF MINNEAPOLIS, MINNESOTA, ASSIGNOR TO HENRY E. VANCE, OF BEMIDJI, MINNESOTA

DESIGN FOR A SUPERSTRUCTURE FOR BEACON TOWERS

Application filed May 23, 1931. Serial No. 39,943. Term of patent 14 years.

To all whom it may concern:

Be it known that I, JAMES E. TATE, a citizen of the United States, residing at Minneapolis, in the county of Hennepin and State of Minnesota, have invented a new, original, and ornamental Design for a Superstructure for Beacon Towers, of which the following is a specification, reference being had to the accompanying drawing, forming part thereof.

The figure is a perspective view of a superstructure for beacon towers, showing my new design.

I claim:

The ornamental design for a superstructure for beacon towers, as shown.

JAMES E. TATE.
